UNITED STATES PATENT OFFICE

2,463,563

GASKET FORMING MACHINE

Joseph Robinson, New York, N. Y., assignor to the
United States of America

Application April 30, 1945, Serial No. 591,107

34 Claims. (Cl. 51—89)

1

The present invention relates to machines for cutting or forming gaskets, and especially gaskets of circular cross-section.

It has been found that the conventional flat gasket, when applied to screw plugs, often becomes twisted so that a tight liquidproof seal is rendered impossible, and this defect becomes even more pronounced in military operations where the gaskets are often handled at night without the benefit of artificial lights.

Gaskets of circular cross-section have heretofore been made by a molding process which is relatively slow, tedious and expensive, and which frequently produces an inferior product due to the formation of "fins" at the joints of the mold sections.

It is an object of the present invention, therefore, to provide an automatically operating machine for forming gaskets of circular cross-section, without fins, and at a relatively high rate of speed.

It is another object of the invention to provide an automatically operating former for gaskets of circular cross-section which may be readily and simply altered to form gaskets of varying cross-sectional diameters.

Other objects and advantages of the invention will be apparent from the following description when taken in connection with the accompanying drawings in which

Figure 1 is a side elevational view of the novel gasket forming machine, parts being broken away.

Figure 2 is a sectional view taken on line 2—2 of Figure 1 and looking in the direction of the arrows.

Figure 3 is a plan view of the machine, partly broken away.

Figure 4 is a sectional view taken on line 4—4 of Figure 1 and looking in the direction of the arrows.

Figure 5 is an elevational view of that end of the machine appearing at the left of Figure 1.

Figure 6 is an enlarged fragmentary view of that portion of the machine directly associated with the cutting wheels.

Figure 7 is an enlarged longitudinal sectional view through the mandrel for supporting the rubber tubing, and related parts, and

Figures 8 and 9 are plan and sectional views, respectively, of one of the gaskets cut by the present machine.

Referring to the drawings, more specifically and particularly to Figures 6 and 7, the numeral 1 indicates a hollow mandrel which telescopically engages and is welded to a hollow shaft 2 mounted in bearings 3. These bearings are mounted on standards 4 (Fig. 5) supported on the mandrel base plate 5 and the latter may be swivelled on the bed of the machine as indicated

2

at 5', and may be locked in its operative position by lock 5''. The hollow shaft 2 extends beyond the bearings 3, and in conjunction with the hollow mandrel 1 may form a conduit for the cuttings of gasket material by merely connecting a suction pump or other source of vacuum to the outer end of the shaft 2 by means of a rubber hose or the like.

The gaskets of circular cross-section are to be cut from tubes of gasket material and one such tube 6 is shown as mounted on the mandrel 1. The pivot 5' just referred to permits the plate 5 to be swung forwardly through an angle of about 5° so that new tubes 6 may be installed on the mandrel from time to time during the operation of the machine. The tube is to be fed along the mandrel 1 and beyond its free end in a step-by-step movement, and a pusher sleeve 7 is slidably mounted on the mandrel for that purpose. A keyway 8 in mandrel 1 and key 9 on sleeve 7 cause the pusher sleeve to rotate with the mandrel and permits axial movement relative thereto. The outer end of the pusher 7 is provided with a reduced portion 10 to receive the adjacent end of the tube 6, and the parts may be additionally connected by an adhesive band 11 or the like, if desired. The opposite end of the pusher sleeve 7 is preferably provided with an outturned flange 12 adapted to be engaged by rollers 13 mounted upon a yoke carried by a bracket 14. The upper end of this bracket encircles a guide rod 15, and an intermediate part thereof is provided with a threaded portion for cooperation with a feed screw 16, to which is imparted an intermittent rotary motion as will appear hereinafter. A handle 17 pivoted on the bracket 14 serves to move the threaded portion of the bracket into and out of engagement with the feed screw, to thereby start or stop the feeding operation, as desired, and to permit the quick return of the bracket to the starting point. This particular mechanism is old in the art and need not be further described.

As the tube 6 is fed along the mandrel 1 a cutter or grinding disc 18 formed of suitable abrasive material or the like is intermittently brought into engagement with the outer surface of the rotating tube 6 during the dwell periods in its longitudinal movement, so as to cut a series of annular grooves therein as indicated at the right hand end of the tube as viewed in Figure 6. The cutter 18 is mounted on the end of the shaft of motor 19, and the latter is fixed to and suspended from a plate 20 having a sliding dove-tail connection with a hanger 21 depending from the rods 15 and 15'. A cam 22 on shaft 23 cooperating with a roller 24 on plate 20 serves to move the cutter 18 into engagement with the tube 6, and one or more springs 25 serve to maintain the roller in contact with the cam and thus move

the cutter away from the tube after each cutting operation. The cutter is preferably provided with a guard casing 26 to confine particles of rubber cut from the tube at each operation.

The inner or final groove for completing each gasket of circular cross-section is formed by an inner cutting wheel or disc 27 of somewhat smaller diameter than the internal diameter of the tube 6, and formed of the same material as cutter 18. This cutter 27 is fixed to the shaft of a motor 28 suspended from a dove-tail plate 29 which is slidably mounted in a hanger 30 slidably mounted on the rods 15 and 15'. The plate 29 is moved laterally of the machine by a cam 31 corresponding to cam 22 for the outer cutter 18, and a spring (not shown) similar to spring 25 serves to return the plate and inner cutter to inoperative position. The hanger itself, and the plate, motor and cutter disc carried thereby may be moved longitudinally of the machine by a closed or barrel cam 32 mounted on a shaft 33. The cam 32 cooperates with a cam roller or follower 34 on the hanger 30 and thus operates to reciprocate the hanger, etc., longitudinally of the machine and thereby move the cutter 27 axially of the tube 6. Springs 35 may be employed for damping this movement of the hanger and the associated cutter.

From the mechanism thus far described it will be apparent that the tube 6 is fed along the rotating mandrel 1 in a step-by-step movement and that the end of the tube will pass beyond the end of the mandrel. During the dwell periods the external cutter disc 18 will be brought into engagement with the outer surface of the tube and cut a rounded annular groove G therein as shown in Figure 6. As the tube 6 passes beyond the end of the mandrel the inner cutter 27 will be brought into engagement with the inner exposed surface of the tube 6 and form a rounded annular groove therein. This inner groove is formed in the plane of the adjacent external groove, and inasmuch as each groove has a depth corresponding to one-half the thickness of the wall of the tube, a ring or gasket A will be cut from the end of the tube, and will have a circular cross-sectional shape as indicated in Figures 8 and 9. Upon the completion of the internal cut the disc 27 is moved radially away from the tube and then withdrawn axially from the tube until its cam 32 again moves it into the tube preparatory to the formation of another gasket. The completed gaskets may be discharged through an outlet chute 36.

As hereinbefore mentioned the mandrel and its supporting mechanism are capable of swinging through an angle of about 5° in a horizontal plane so as to facilitate the placing of the tubes of gasket material thereon. In order to maintain the mandrel in its operative position during the cutting operations, to prevent "whipping" of the free end of the mandrel and tube, to provide an anvil against which the internal cutter may operate, and to generally support the free end of the mandrel, a rotatable ring 37 is provided for encompassing the outer end of the tube and the free end of the mandrel. This ring is mounted on a ball bearing race 38 supported on a standard 39 fixed to the base plate 5.

The ring 37 is preferably provided with an integrally connected pulley wheel 40 with which is associated a belt 41, driven by a pulley wheel 42 mounted on a shaft 43 supported in bearings 44 on the plate 5. The opposite end of shaft 43 is provided with a pulley wheel 45 driven by

belt 46 associated with a pulley wheel 47 fixed to the mandrel 1. These pulley wheels are all of the same diameter so that the supporting ring or anvil 37 will be driven at the same speed as the mandrel itself, thereby avoiding any relative rotary movement between the ring 37 and tube 6.

The mechanisms for driving and synchronizing the various parts of the machine are old and well known in the art as evidenced, for example, in the patent to Hammond et al. No. 1,685,127, and a detailed description of such mechanisms is therefore believed to be neither necessary nor desirable. It is to be noted, however, that the motor 50 constitutes the main source of power, and imparts the desired rotary movement to mandrel 1 and gasket tube 6, through pulley wheels 51 and 52 and belt 53. This motor also drives, through sprocket gearing 54 and 55, a Geneva wheel 56, which through gear wheels 57, 58 and 59 imparts the desired start and stop movement to the feed screw 16, thereby producing the necessary dwell periods in the longitudinal movement of the tube 6 to permit the cutters 18 and 27 to perform their functions. The cam shaft 33 is driven by the sprocket chain 55, and a gear wheel on this shaft meshes with a gear wheel 60 on shaft 23 to operate the cams 22 and 31.

Certain refinements in the mechanism, which tend to promote ease of operation etc., but which are old in the art and form no part of the invention claimed herein, need not be described in detail.

In the operation of the machine, the bracket 14 is first moved to its rearward position, as is also the pusher tube 7. The lock or clamp 5" is next released and the plate 5 and related parts swung through an arc of 5° to permit the placing of a tube 6 of gasket material on the mandrel 1. The rear end of the tube is forced over the reduced portion 10 of the pusher sleeve 7 and a band of adhesive tape or the like 11 may be employed to overlap the joint and form an additional securing means, if desired. The plate assembly is then returned to its normal position and locked by means of the clamp 5". The motors are then started, thereby rotating the mandrel 1 and tube 6, as well as the cutters 18 and 27, it being understood of course that the cutters are rotated in a direction opposed to the direction of rotation of the tube. The feed screw 16 and pusher 7 cause the tube to be fed forwardly step-by-step toward the cutters, and as the adjacent end of the tube reaches the external cutter 18 the series of grooves heretofore mentioned are formed in the outer wall of the tube. The cutting position of the inner cutter 27 is slightly beyond the outer end of the mandrel, and the internal grooves which complete the gaskets, and sever them, are formed after the end of the tube passes the end of the mandrel. In this cutting operation the ring 37 which supports the outer end of the tube and mandrel and extends slightly beyond the latter, serves as an anvil to support the free end of the tube when the inner cutter is applied to the inner wall thereof in forming and cutting off the gasket.

If it were desired to form gaskets having a different cross-sectional area from that shown in Figures 8 and 9, it is only necessary that a tube be employed having a wall of the thickness corresponding to the diameter desired in the completed gasket, and that cutting discs of the required peripheral contour be substituted for

those employed in the embodiment of the invention illustrated herein.

In accordance with the patent statutes I have described what I now believe to be the preferred embodiment of the invention, but it is to be understood that various changes may be made in the operating mechanisms without in any way departing from the essence of the invention, and it is intended that all such alterations be included within the scope of the appended claims. 10

I claim:

1. In a machine for forming gaskets of circular cross-section, a mandrel for supporting a tube of gasket material, means for rotating the tube, and means for forming a series of aligned grooves in the exterior and interior of the tube, said means being constructed and arranged to form grooves of sufficient depth so that the interior and exterior grooves merge to form complete breaks in the tube.

2. In a machine for forming gaskets of circular cross-section, a mandrel for supporting a tube of gasket material, and rotating cutters for forming annular aligned grooves in the exterior and interior of the tube, said cutters being constructed and arranged to form grooves with walls convexed inwardly and of sufficient depth so that interior and exterior grooves merge to form complete breaks in the tube.

3. In a machine for forming gaskets of circular cross-section, a mandrel for supporting a tube of gasket material, means for cutting annular merging grooves on the interior and exterior of the tube, and means for advancing the tube longitudinally step-by-step.

4. In a machine for forming gaskets of circular cross-section, a mandrel for supporting a tube of gasket material, means for cutting merging grooves on the interior and exterior of the tube, and means for moving the first-mentioned means toward and from the tube.

5. In a machine for forming gaskets of circular cross-section, a mandrel for supporting a tube of gasket material, means for cutting merging grooves on the interior and exterior of the tube, means for moving the first-mentioned means toward and from the tube, and means for advancing the tube longitudinally step-by-step.

6. In a machine for cutting gasket material, a mandrel for supporting a tube of gasket material, means for moving said tube axially relative to said mandrel, means for cutting a groove on the interior of the tube, and means for moving the first-mentioned means into and out of the tube.

7. In a machine for cutting gasket material, a mandrel for supporting a tube of gasket material, means for moving said tube step-by-step, means for cutting a groove on the interior of the tube, means for moving the first-mentioned means into and out of the tube and toward and from the inner wall of the tube.

8. In a machine for cutting gasket material, a mandrel for supporting a tube of gasket material, means for moving said tube axially step-by-step, a cutter for forming grooves on the interior of the tube, means for moving the cutter into and out of the tube, and a rotary cam for periodically moving the cutter toward and from the inner wall of the tube.

9. In a machine for cutting gasket material, a mandrel for supporting a tube of gasket material, means for moving said tube axially relative to said mandrel, a cutter for forming grooves on the interior of the tube, a rotary cam for moving the

cutter into and out of the tube, and means for moving the cutter toward and from the inner wall of the tube.

10. In a machine for forming gaskets of circular cross-section, a mandrel for supporting a tube of gasket material, inner and outer cutters for forming merging grooves in the inner and outer walls of said tube, means for moving said cutters toward and from the tube, means for moving the inner cutter into and out of said tube, and means for advancing the tube longitudinally step-by-step.

11. In a machine for forming gaskets of circular cross-section, a mandrel for supporting a tube of gasket material, inner and outer rotary cutters for forming merging grooves in the inner and outer walls of said tube, rotary cams for moving the cutters toward and from the tube, a rotary cam for moving the inner cutter into and out of the tube, and means advancing the tube longitudinally step-by-step.

12. In a machine for cutting gasket material, a mandrel for slidably receiving a tube of gasket material, means for moving the tube longitudinally of the mandrel step-by-step, and means for cutting grooves on the inner wall of the tube.

13. In a machine for cutting gasket material, a mandrel for slidably receiving a tube of gasket material, a pusher sleeve keyed to the mandrel for cooperation with the tube, and means for cutting grooves on the inner wall of the tube.

14. In a machine for cutting gasket material, a mandrel for slidably receiving a tube of gasket material, a pusher sleeve keyed to the mandrel, means for moving the pusher sleeve and tube axially of the mandrel, and means for cutting grooves on the inner wall of the tube.

15. In a machine for cutting gasket material, a mandrel for slidably receiving a tube of gasket material, an intermittently operated lead screw, means threaded to the screw for advancing the tube axially of the mandrel, and a cutter for forming grooves on the inner wall of the tube.

16. In a machine for cutting gasket material, a mandrel for slidably receiving a tube of gasket material, means for advancing the tube step-by-step beyond the end of the mandrel, and means for cutting a groove in the inner wall of the tube beyond the end of the mandrel.

17. In a machine for cutting gasket material, a mandrel for slidably receiving a tube of gasket material, means for advancing the tube step-by-step beyond the end of the mandrel, a rotary cutter, and means for moving the cutter toward and from the inner wall of the tube beyond the end of the mandrel.

18. In a machine for cutting gasket material, a rotatable shaft, a mandrel having one end secured to the shaft, said mandrel adapted to slidably receive a tube of gasket material, means for moving the tube step-by-step along the mandrel and beyond the free end thereof, and means for entering said tube and forming grooves in its inner wall beyond the free end of the mandrel.

19. In a machine for forming gaskets, a rotatable member, a mandrel having one end fixed thereto, said mandrel adapted to slidably receive a tube of gasket material, means for moving said tube step-by-step beyond the free end of the mandrel, rotatable means for supporting the free end of the mandrel and the adjacent end of the tube, and means for cutting a gasket from the end of said tube.

20. In a machine for forming gaskets, a rotatable member, a mandrel having one end fixed

thereto, said mandrel adapted to slidably receive a tube of gasket material, means for moving an end of the tube beyond the free end of the mandrel, a rotatably-mounted ring for engaging and supporting said end of the tube, and means for cutting a gasket from the end of said tube.

21. In a machine for cutting gasket material, a rotatable member, a mandrel having one end fixed thereto, said mandrel adapted to slidably receive a tube of gasket material, means for moving an end of the tube beyond the free end of the mandrel, a cutter for forming grooves on the inner surface of the free end of the tube, and a travelling anvil for supporting said end of the tube.

22. In a machine for forming gaskets, a rotatable mandrel adapted to slidably receive a tube of gasket material, means for feeding the tube along the mandrel to expose an end thereof beyond the adjacent end of the mandrel, a rotatable ring having an internal diameter corresponding to the exterior diameter of the tube and encompassing the exposed end thereof, and a cutter for intermittently engaging the inner surface of the exposed end of the tube.

23. In a machine for forming gaskets, a rotatable mandrel adapted to slidably receive a tube of gasket material, means for feeding the tube along the mandrel to expose an end thereof beyond the adjacent end of the mandrel, a rotatable ring having an internal diameter corresponding to the exterior diameter of the tube and encompassing the exposed end thereof, a cutter for intermittently engaging the inner surface of the exposed end of the tube, and means for driving the ring at a speed corresponding to that of the mandrel.

24. In a machine for forming gaskets, a rotatable mandrel adapted to slidably receive a tube of gasket material, means for feeding the tube along the mandrel to expose an end thereof beyond the adjacent end of the mandrel, a rotatable ring encompassing the exposed end of the tube, a cutter for intermittently engaging the inner surface of the exposed end of the tube, and a driving connection between the mandrel and ring.

25. In a machine for forming gaskets, a rotatable mandrel adapted to slidably receive a tube of gasket material, means for feeding the tube along the mandrel to expose an end thereof beyond the adjacent end of the mandrel, a ring encompassing the exposed end thereof, a ball race rotatably supporting the ring, a cutter for engaging the inner surface of the tube, and means for rotating the ring.

26. A machine including a mandrel adapted to support a tube of material, means for moving said tube lengthwise relative to said mandrel, and means for cutting a series of annular grooves on the exterior of the tube, said mandrel being constructed and arranged to hold said tube sufficiently rigid to prevent flexing of said tube.

27. A machine including a mandrel adapted to support a tube of material, means for moving said tube step-by-step axially relative to said mandrel, and means for making annular cuts in said tube.

28. A machine including a mandrel adapted to support a tube of material, a rigid pusher for pushing said tube along said mandrel, means for operating the pusher step-by-step and means

5 synchronized with the pusher operator for making annular cuts in said tube.

29. A machine including a mandrel adapted to support a tube of material, means for moving said tube axially relative to said mandrel, a cutter for making annular cuts on the interior of the tube, and means for moving said cutter into the tube to engage the interior of the tube for cutting.

30. In a machine for cutting rings from the forward end of a tube of material, a mandrel for supporting said tube, means for moving said tube step-by-step beyond the forward end of said mandrel, and means for cutting a ring from the forward end of said tube.

15 31. In a machine for cutting rings from the forward end of a tube of material, a mandrel for supporting said tube, means for moving said tube step-by-step beyond the forward end of said mandrel, and means for cutting a ring from the forward end of said tube, said last mentioned means comprising a cutter movable into the forward end of said tube.

25 32. In a machine for forming ring gaskets, a mandrel for supporting a tube of gasket material, and rotary cutters for forming annular aligned cuts in the exterior and interior of the tube, said cutters being constructed and arranged to form cuts of sufficient depth so that the interior and exterior cuts merge to form complete breaks in the tube.

35 33. In a machine for forming ring gaskets, means for supporting a tube of gasket material, means for moving said tube axially, cutting means for forming annular cuts in the exterior surface of said tube, cutting means axially offset from said first-mentioned cutting means for forming annular cuts in the interior surface of the tube, and means for synchronizing the movement of said tube and the operation of said cutting means 40 whereby interior and exterior cuts merge to form complete breaks in the tube.

45 34. A machine including a mandrel adapted to support a tube of material, a pusher tube slidably mounted on said mandrel and having means at its forward end for engaging said first-mentioned tube, means for operating the pusher tube step-by-step, and means synchronized with the means for operating the pusher tube for making annular cuts in the first-mentioned tube.

JOSEPH ROBINSON.
